UNITED STATES PATENT OFFICE.

THOMAS CHARLES RANDALL, OF NEWPORT, RHODE ISLAND.

HAIR-DRYING FRAME.

1,141,826.

Specification of Letters Patent. Patented June 1, 1915.

Application filed December 2, 1914. Serial No. 875,116.

To all whom it may concern:

Be it known that I, THOMAS C. RANDALL, a citizen of the United States, and a resident of Newport, in the county of Newport and State of Rhode Island, have invented a new and Improved Hair-Drying Frame, of which the following is a full, clear, and exact description.

This invention relates to an appliance adapted to be used in drying ladies' hair after the same has been washed, or after bathing, whereby the hair is supported off the shoulders to enable the air to obtain better access thereto and to enable an attendant to more easily rub the hair dry and comb it.

The general objects of the present invention are to improve and simplify the construction of devices of the character referred to so as to be durable and efficient in use, comparatively simple and inexpensive to manufacture, and so designed that it can be readily collapsed when not in use, so as to occupy only a small space.

A further object of the invention is the provision of a frame which is applied to the back of the neck and supported in place by shoulder-engaging braces and by tie strings or the like which pass forwardly over the front of the head.

Still another object of the invention is the provision of a hair drying frame whereby the hair can be spread over a wide area, and by means of pins on the frame different portions of the hair after being dried or combed can be kept separated from the undried or uncombed portions.

With such objects in view, and others which will appear as the description proceeds, the invention comprises various novel features of construction and arrangement of parts which will be set forth with particularity in the following description and claims appended hereto.

In the accompanying drawing, which illustrates one embodiment of the invention and wherein similar characters of reference indicate corresponding parts in all the views, Figure 1 is a perspective view of the appliance shown in use; Fig. 2 is an enlarged plan view thereof detached from the user; Fig. 3 is a plan view of the appliance folded or collapsed as when not in use; and Fig. 4 is a detail view of the detachable connecting

means between the neckpiece and a part of the frame.

Referring to the drawing, the frame A of the device embodies an arc-shaped rest or neckpiece 1 which is adapted to fit and bear against the back of the neck, and the ends 2 of this neckpiece 1 are attached by strings 2 which are adapted to extend upwardly along the sides and front of the head where the ends of the strings are tied. By this means the frame of the appliance is held attached to the head. The structure of the frame may be of any desired design but in the present instance the frame comprises a pair of cross bars 3 and 4 which are pivotally connected at 5 like a pair of scissors, and the bar 3 is detachably connected at 6 with the neckpiece 1, as shown in Fig. 2, and the bar 4 is pivotally connected at 7 with the neckpiece. The detachable connection at 6 comprises a stud 6^a, Fig. 4, on the bar 5, which stud is adapted to engage in a socket or opening 6^b on the neckpiece 1. On the outer ends of these bars is carried an arcuate member or rail 8 over which the hair hangs to thereby keep the hair off the shoulders of the person wearing the device. This member 8 is made in two sections hingedly connected at 9, and the bar 3 is pivotally connected at 10 with the section a of the member 8, and the bar 4 is pivotally connected at 11 with the section b. If desired, another bar 8^a may be pivotally connected at 12 and 13 with the bars 3 and 4, this member 8^a being made in two sections hingedly connected at 14. The frame thus constructed is adapted to be supported approximately in a horizontal position, and in order to relieve the head from the weight there are shoulder-engaging braces 15 and 16 which are hingedly connected respectively at 17 and 18 to the bars 3 and 4 of the frame. On the lower ends of these braces 15 and 16 are pivotally mounted members 15^a and 16^a for bearing on the shoulders, as clearly shown in Fig. 1. By making the members 8 and 8^a each in two parts hingedly connected together by pivotally connecting the said parts to the bars 3 and 4 by pivotally connecting these bars and by detachably connecting the bar 3 with the neckpiece 1, the whole frame can be folded from the open or extended position in Fig. 2 to the closed position shown in Fig. 3.

In order to facilitate the drying and combing of the hair the frame is provided with means whereby each portion of the hair as it is dried or combed can be kept separate from the other portions, and for this purpose the outer part of the frame, preferably the member 8, is provided with a plurality of fingers or pins 19 which are hingedly connected at 20 to the member 8, whereby these fingers or pins can be thrown to an upright position, as shown in Fig. 1, or turned down parallel with the frame when not in use. It will be understood that when a portion of the hair is dried or combed, that portion will be laid on the frame between two of the fingers and then unother lot of hair is taken up for drying or combing, after which this portion is placed between two other pins or fingers and in this manner the whole mass of hair is attended to.

From the foregoing description taken in connection with the accompanying drawing, the advantages of the construction and method of operation will be readily understood by those skilled in the art to which the invention appertains, and while I have described the principle of operation, together with the device which I now consider to be the best embodiment thereof, I desire to have it understood that the device shown is merely illustrative and that such changes may be made when desired as are within the scope of the appended claims.

Having thus described my invention, I claim as new and desire to secure by Letters Patent:

1. A hair drying device comprising a frame consisting of a pair of arcuate members pivotally connected together, a pair of cross members pivotally connected together and pivotally connected respectively with the first mentioned members at points at opposite sides of the pivotal connection between such first mentioned members, and a neck piece permanently pivotally connected with one of the cross members and detachably connected with the other cross member, and when connected with such other cross member the arcuate and cross members are held in fixed relation, the points of pivotal connections having their axes parallel, whereby the parts of the frame are foldable in a single plane.

2. A hair drying device comprising a frame including a neckpiece to engage the back of the neck, and tie strings connected with the neckpiece to fasten the device to the head, members pivotally carried by the frame and curved pieces pivotally connected

with the lower ends of the members and adapted to rest on the shoulders to support the frame in outstanding position.

3. A hair drying device comprising a frame, means for mounting the frame on the body of a person at the back of the neck, and a plurality of members movably mounted on the frame and spaced apart, whereby different portions of the hair after being combed or dried can be kept separate from other portions.

4. A hair drying appliance of the class described, comprising a frame adapted to be applied to the rear of the head at the neck of the user, and a plurality of spaced pivotally mounted fingers on the frame for holding separately dried or combed portions of the hair.

5. An appliance of the class described comprising a frame including a pair of concentric arcuate members each composed of sections pivotally connected together, members pivotally connected with the first mentioned members and holding the same normally in parallel relation, shoulder-engaging devices pivotally connected with the frame, and a neck-engaging device connected with the second mentioned members and co-operating therewith for holding the frame open.

6. A device of the class described comprising a neckpiece, a pair of hingedly connected cross members, a pivotal connection between one of the cross members and neckpiece, a detachable connection between the other cross member and neckpiece, and a hair supporting member composed of pivotally connected parts and pivotally connected with the said cross member, whereby the device can be folded when not in use.

7. A device of the class described comprising a neckpiece, a pair of hingedly connected cross members, a pivotal connection between one of the cross members and neckpiece, a detachable connection between the other cross member and neckpiece, a hair supporting member composed of pivotally connected parts and pivotally connected with the said cross member, whereby the device can be folded when not in use, and shoulder-engaging braces pivotally connected with the said cross members.

In testimony whereof I have signed my name to this specification in the presence of two subscribing witnesses.

THOMAS CHARLES RANDALL.
